UNITED STATES PATENT OFFICE.

OLIVIER PIETTE, OF PARIS, FRANCE, ASSIGNOR TO SOCIÉTÉ ANONYME DES FOURS À COKE SEMET-SOLVAY & PIETTE, A CORPORATION OF THE KINGDOM OF BELGIUM.

COKING-OVEN.

1,370,481.

Specification of Letters Patent. Patented Mar. 1, 1921.

Application filed November 6, 1918. Serial No. 261,424.

To all whom it may concern:

Be it known that I, OLIVIER PIETTE, a citizen of Belgium, and a resident of Paris, France, have invented certain new and useful Improvements in Coking-Ovens, of which the following is a specification.

This invention relates to improvements in coking ovens with by-product recovery and heat regeneration by reversal of the flow of the gases and the air for combustion and has for its object the provision of means whereby the reheating of the products of combustion, after they have given up a portion of their heat to the regenerators, is prevented.

In a certain type of horizontal ovens with vertical flues and transverse regenerators, the two regenerator chambers provided for one phase of the heat recovery and which are located on the same side of the longitudinal center line of the battery are of equal dimensions and communicate with one another by ducts whose cross sectional area increases proportionately to their distance from the chimney.

The products of combustion, after being partially cooled in the checker work in the first or primary regenerator chambers pass downwardly in the same through the above mentioned ducts into the secondary regenerator, and passing upwardly through the checker work therein, escape to the chimney by means of the flues constituted by the free space above the checker work and under the arch of the secondary regenerator chamber. Said arches being close to the hot sole flues of the retort are heated thereby to a temperature higher than that of the products of combustion after said products leave the secondary checker work. In their passage through said flues the products abstract heat from the arch whereby their temperature is again raised, and then escape to the chimney thus wasting the heat abstracted from the arches.

The annexed drawings illustrate a construction embodying my invention.

Figure 1 is a vertical longitudinal half-section through an oven and its regenerator foundation.

Fig. 2 is a partial vertical transverse section, and

Fig. 3 is a vertical section adjacent the reversing valve, the line A—B representing the axis of said valve.

Fig. 4 is a partial plan section on line 4—4 of Fig. 3.

Fig. 5 is a partial plan section on line 5—5 of Fig. 3.

In the following description primed reference numbers are employed to designate similar members or structures to those designated by the original numbers, but located on the opposite side of the battery center line.

In the annexed drawings 1 indicates a retort provided with doors, charging holes and off-take in the usual manner. Adjacent to the retort are side walls in which are formed a plurality of vertical combustion flues 2 and 2' superimposed over gas chambers 3 and 3' with which they communicate by means of ports 4 and 4'. The combustion flues 2 and 2' terminate at their upper ends in a horizontal flue 5 extending transversely to the battery center line and providing communication between the flues 2 and 2'. Directly beneath each retort and extending parallel to the same and transversely to the battery center line are provided sole flues which are divided into halves 6 and 6' by wall 7. The sole flues 6 and 6' are each connected by twyars 8 and 8' with the groups of combustion flues 2 and 2' respectively, each half sole flue connecting with the adjacent group of combustion flues in one wall only, for example, sole flue 6 communicates with combustion flues 2 by means of twyars 8. Each sole flue 6' communicates with the regenerator chamber d by means of the port 9' controlled by damper 10'; sole flue 6 connecting in like manner, though not shown on the drawings, with regenerator chamber c by means of port 9 controlled by damper 10. Beneath the retorts and extending transversely thereto and parallel to the battery center line are located the regenerator chambers c and c' and d and d', the secondary regenerators c' and d' being adjacent to a center line, but on opposite sides thereof. The primary regenerator c is located between c' and one face of the battery and the primary regenerator d between the regenerator d' and the opposite face of the battery.

The regenerators c and c' and d and d' are connected on the foundation level by a plurality of ducts 11 and 11' respectively. All regenerator chambers are provided with checker-work of refractory material, the

chambers *c* and *d* being substantially filled with the same, while enough space is left clear under the arch of chambers *c'* and *d'* to provide flues of ample cross-sectional area 5 to conduct the products of combustion by passages *h*³ to the chimney. Immediately above the regenerator chambers *c'* and *d'* and between same and the sole flues are provided air flues or channels *g* which conduct 10 the air for combustion from the atmosphere to the reversing valve.

In the foundation of the battery and extending parallel to its longitudinal center line is provided a plurality of flues *h* shown 15 by dotted lines in Fig. 4 which terminate at the chimney end of the battery in a transverse flue *h'* communicating with the air inlet to the reversing valve by means of flue *h*² and which are open to the atmosphere at 20 the opposite end of the battery.

The gas is introduced into the gas chambers 3 and 3' by groups of gas pipes 12 and 12' which are each provided with stop valves whereby the flow of gas to the chambers 25 may be regulated or stopped as required.

My improved oven operates as follows:

Cold air for combustion is conducted through flues *h* and *g* absorbing therein the heat radiated from the floor of the regenerator chambers to the foundation and from 30 the sole flues to the secondary regenerator arch. It being assumed that the right hand half of the oven as shown in Fig. 1 is to be heated, the air will be directed through one 35 of the passages *h*³ into the secondary regenerator chamber *d'* by means of the reversing valve *i*, will descend through same, pass through the flue 11' and ascending through regenerator chamber *d* will be heated therein 40 and flow into the sole flue 6' whence it will be conducted by twyters 8' into combustion flues 2' where it will meet the gas admitted from chambers 3' by means of ports 4', and will ignite. The products of combustion 45 pass upwardly in flues 2', into the horizontal flue 5 from whence they travel downwardly in the flues 2 and into the regenerator chamber *c* (where they surrender a portion of their heat to the checker work) by means of 50 twyters 8, sole flue 6 and port 9. Passing downwardly through the regenerator *c* they are admitted by flues 11 to the chamber *c'* which they traverse upwardly, giving up a further portion of their heat to the checker 55 work therein, and escape to the chimney

through the flue in the clear part of the chamber *c'*. When the checker work in regenerator chambers *c* and *c'* has acquired sufficient heat from the products of combustion, the flow of the air and products of combustion is reversed by properly positioning the reversing valve *i*, whereby air from flues *g* and *h* is admitted to regenerator *c'* through the other passages *h*³ and regenerator *d'* is placed in communication with the chimney, 60 gas being admitted to the chambers 3 and excluded from chambers 3'. Combustion will now take place in the flues 2 where the heated air and gas mix and ignite. The products of combustion will escape to the 70 reversing valve and the chimney by the same path as that followed by the air before reversal but will flow in an opposite direction.

What I claim as my invention and desire 75 to secure by Letters Patent of the United States is:—

1. In combination, in a coking oven having transverse primary and secondary regenerator flues disposed below the combustion chambers and means for reversing the direction of the flow of the products of combustion, channels located between such secondary regenerator flues and the combustion chambers, each of said channels at one end 85 constituting an air inlet, and at the other end being connected with the secondary regenerator flues, substantially as and for the purpose described.

2. In combination, in a coking oven having transverse primary and secondary regenerator flues disposed below the combustion chambers, said secondary regenerator flues being of less height than said primary flues, means for reversing the direction of 95 the flow of the products of combustion, and channels located between such secondary regenerator flues and the combustion chambers, each of said channels at one end constituting an air inlet, and at the other end 100 being connected with the secondary regenerator flues, substantially as and for the purpose described.

In witness whereof I have signed this specification in the presence of two witnesses. 105

OLIVIER PIETTE.
